CABLE-PULLING CLAMP.

1,244,043.

Specification of Letters Patent. Patented Oct. 23, 1917.

Application filed March 21, 1917. Serial No. 158,446.

To all whom it may concern.:

Be it known that I, WILLIAM G. B. EULER, a citizen of the United States, residing at the city and county of San Francisco and State of California, have invented certain new and useful Improvements in Cable-Pulling Clamps, of which the following is a specification.

My invention relates to a cable or wire-pulling clamp, of the type technically known as a "come-along."

These devices are used principally by linemen in the construction and repair of electric transmission lines, and are frequently operated under the most difficult conditions, as, for example, by a lineman clinging to the top of a pole, or sitting or standing upon a cross arm many feet above the ground. The ideal clamp for such use is one that is as light as is consistent with the necessary strength, which may be operated entirely by one hand, and which can be tightened upon the wire, with comparatively little effort, and when so tightened will establish a sufficient grip upon the wire to prevent slipping even under the greatest strains used in practice. In this connection it is well to note that the normal strain upon an aerial power conductor, in the systems using long spans between supports, may amount to 3000 pounds or over, and that the pull upon a clamp, when stringing or repairing such a cable, may reach 4000 pounds.

The object of my invention is to provide a clamp having the desirable features mentioned above. In addition, my clamp is of such construction that the clamping effect on the wire does not depend on the pull on the clamp, so that the latter may be loosened, to permit the wire to be slipped through it, without relieving the pulling strain. A further advantage of my clamp resides in the fact that it may be readily dissociated for the replacement or repair of any of its parts.

With these and other objects in view, my invention will now be described in its preferred form, but it is to be understood that changes, within the scope of the claims hereinafter appended, may be made in the form and construction of the device without departing from the spirit of the invention.

In reading the following description, ref-

erence should be had to the accompanying drawings, wherein—

Figure 1 is a side elevation of my clamp attached to a wire or cable.

Fig. 2 is a front elevation of the clamp, enlarged, showing the parts in position for application to a wire or cable.

Fig. 3 is an end elevation of the clamp as shown in Fig. 2.

Fig. 4 is a transverse section, enlarged, taken on the line 4—4 of Fig. 1, the wire being omitted.

In the drawings, the reference numerals 1 and 2 designate the two adjacent co-acting jaws of my clamp, which are hinged together at one side by a pin 3, passing through adjacent interfitting ears 4 and 5 of said jaws 1 and 2 respectively. The inner faces of said jaws are formed with co-acting, complementary grooves 6, Figs. 2, 3 and 4, parallel with the hinge pin 3, for receiving the wire or cable 7, Fig. 1, which is to be clamped. The outer portions of said jaws are chamfered, as at 8, to permit the device to be easily slipped over the wire without first spreading the jaws.

The jaws 1 and 2 are held together, to clamp the wire, by means of a clamping bolt 9, adapted to lie within alined notches 10 and 11 cut in the outer edge portions of the jaws 1 and 2 respectively. The head 12 of said bolt is swiveled upon a lineally disposed pin 13 secured to the outer surface of the jaw member 2 by any suitable means, as for example by rivets 14, Figs. 2 and 3. Said bolt 9 is thus adapted to be swung out of the way, as shown in Figs. 2 and 3, to permit the clamp to be slipped over the wire. The end portion of said bolt is threaded, as at 15, and a clamping nut 16 is screwed thereover, said nut being provided with a handle 17, and retained against complete removal from said bolt, as by means of a split-pin 18.

In order to hold the clamp on the wire before the bolt is tightened, I provide springs 19, mounted in suitable sockets drilled into the jaw 2 from the rear edge thereof, the force of said springs acting, through lineally movable pins 20, against the faces 21 of the hinge lugs 4 of the jaw 1, in such a manner as to hold said jaws closed. Thus the operator, using but one

hand, can slip the clamp over the wire, the latter seating within the grooves 6; and, the springs 19 holding the jaws 1 and 2 closed, the clamp remains on the wire, in any position, while the operator, with the same hand, if necessary, swings the clamping bolt 9 into place and tightens the nut 16.

One of the jaws, as for example the jaw 2, is provided with a grooved extension 22 at one end, the groove in which continues the groove of the jaw. This extension is parallel with the wire or cable 7, and the latter lies in its grooved face. The extension 22 is formed with an eye or socket 28, 15 to which the tackle or other pulling means, not shown in the drawings, may be attached.

The advantages of my clamp will now be more readily appreciated. The parts are all held together, and, as before stated, 20 may be easily applied to the wire with one hand, and tightened without the use of special tools. However, by making the pin 3 removable, the entire clamp may be quickly taken apart for the repair or 25 replacement of any of its parts. Moreover the pull being taken by the fixed lug or extension 22, the clamping action upon the wire is entirely independent thereof, so that the wire may be slipped through the clamp, 30 if necessary, without relieving the pulling strain.

I claim:—

1. A cable-pulling clamp comprising a pair of opposing jaws having interfitting ears 35 pivotally connected, a spring actuated pin slidably seated in one of said jaws and bearing on the ear of the other jaw for normally holding said jaws together, and means for securing said jaws in clamping 40 relation.

2. A cable-pulling clamp comprising a pair of opposing jaws having interfitting ears pivotally connected, a spring actuated pin slidably seated in one of said jaws and 45 bearing on an ear of the other jaw for normally holding said jaws together, a clamp-

ing bolt for securing said jaws in clamping relation, a pivotal connection between said bolt and one of said jaws, whereby said bolt may be swung clear of the other jaw, and a 50 handled nut for clamping said bolt.

3. A cable-pulling clamp comprising a pair of opposing pivotally connected groove-faced jaws, means for securing the same in clamping relation, and a connection carried 55 by one of said jaws for attachment to a pulling means, said connection being a cable-supporting extension of one of the jaws in line with its grooved face.

4. A cable-pulling clamp comprising a 60 pair of opposing pivotally connected groove-faced jaws having interfitting ears, a spring actuated pin slidably seated in one of said jaws and bearing on an ear of the other jaw for normally holding said jaws together, 65 one of said jaws having a cable-supporting extension in line with its grooved face for attachment to a pulling means, a clamping bolt for securing said jaws in clamping relation, a pivotal connection between said 70 bolt and one of said jaws, whereby said bolt may be swung clear of the other jaw, and a handled nut for clamping said bolt.

5. A cable-pulling clamp comprising a 75 pair of opposing connected jaws, a spring normally holding said jaws together, a clamping bolt for securing said jaws in clamping relation, a pivotal connection between said bolt and one of said jaws, whereby said bolt may be swung clear of 80 the other jaw, a handled nut for clamping said bolt, and a longitudinally grooved cable supporting extension of one of said jaws for attachment to a pulling means.

In testimony whereof I have signed my 85 name to this specification in the presence of two subscribing witnesses.

WILLIAM G. B. EULER.
